UNITED STATES PATENT OFFICE.

WILLIAM H. STABLER AND EMMET E. CALDWELL, OF BALTIMORE, MARYLAND,
ASSIGNORS TO AMERICAN CAN COMPANY, A CORPORATION OF NEW JERSEY.

CAN-END LINING AND MARKING MACHINE.

1,318,416.

Specification of Letters Patent. Patented Oct. 14, 1919.

Application filed July 24, 1916. Serial No. 110,887.

To all whom it may concern:

Be it known that we, WILLIAM H. STABLER and EMMET E. CALDWELL, citizens of the United States, residing at the city of Baltimore, in the State of Maryland, have invented certain new and useful Improvements in Can-End Lining and Marking Machines, of which the following is a specification.

The hereinafter described invention relates 10 to an organized apparatus for stamping or embossing or otherwise marking sanitary can ends with a sign, word or symbol by which cans sealed with such ends may be easily identified or recognized.

15 In the past it has been the practice of the manufacturer to so mark can ends and apply the ring liners in separate machines.

The present invention comprises a machine which marks the can ends preferably 20 substantially simultaneously with the application of the ring liners to the same, thus dispensing with the additional labor, time and expense involved in operating two separate and distinct machines.

25 The combination of mechanism which is the subject of this invention does or may preferably comprise such devices for cutting and applying ring liners to can ends as are shown and described in Patent No. 1,162,234 30 granted to Gray Nov. 30, 1915; said patent may be referred to for an understanding of the actuating mechanism which is omitted from the following illustration and description.

35 With such object in view, as well as other advantages which may be incident to the use of the improvements, the invention consists in the parts and combinations thereof hereinafter set forth and claimed, with the understanding that the several necessary elements constituting the same may be varied 40 in proportions and arrangement without departing from the nature and scope of the invention.

45 In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:—

50 Figure 1 is a plan view of the machine partly in section.

Fig. 2 is a vertical section on a larger scale on line II—II of Fig. 1, with the dies separated.

Fig. 3 is a similar view with the dies brought together. 60

Fig. 4 is a vertical section substantially on line IV—IV of Fig. 1.

Figs. 5, 6 and 7 are detail vertical sections on a larger scale illustrating the means for applying the ring liners. 65

Referring to the drawings, 1 indicates any suitable form of a supporting frame capable of sustaining the working parts of the apparatus, and within which frame is secured a stationary supporting table or disk 2. 70 Through a bearing 3 depending from said disk extends a vertically disposed driven shaft 4. To the upper end of this vertical shaft is keyed or otherwise secured a horizontally disposed turret or carrier member 5, 75 which is held a slight distance above the stationary table member 2. An intermittent or step rotation is imparted to the centrally disposed shaft 4 and the horizontally disposed turret or carrier member 5 by any 80 suitably driven mechanism preferably by means such as that shown in said Patent No. 1,162,234.

From the sides of the machine frame and in substantial alinement with the upper face 85 of the stationary table 2 and the upper face of the turret or carrier 5 respectively, project brackets 9 and 10, which support respectively a holder 11 adapted to hold a stack of can ends 13 and a holder 12 adapted to hold 90 a stack of disk blanks 14. The disk blanks 14 are successively delivered from the holder 12 into one of a plurality of circumferentially disposed vertical openings 15 in the turret or carrier 5 and onto a circumferentially disposed seat or shoulder 16 within the said opening for receiving and supporting the said disk blanks, by a suitable feed mechanism (not shown), the said blanks being guided into the positioned opening 15 100 of the turret or carrier member 5 by means of a lateral guide-way 15' formed in the upper face of the said turret or carrier member, there being one such guide-way 15' for each of the said openings 15. The can ends 105 13 to be lined and marked are successively removed from the holder 11 and positioned on the stationary table 2 immediately beneath one of the series of the vertically disposed circumferential openings 15 of the tur- 110

ret or carrier 5 by a feed means (not shown), and the said can end as fed onto the said table or platform 2 moves within one of a series of lateral guide cut-outs 13' formed 5 in the under face of the turret or carrier 5 and which communicates respectively with the circumferentially disposed vertical openings 15 thereof, so that the peripheral wall of the flange of the can end 13 will be 10 braced thereby and held against displacement.

Supported above the turret or carrier 5 by any suitable means and over the path of travel of the openings 15 therein is a vertically reciprocating cross head 22' operated preferably by such means as those shown in Patent 1,162,234. This cross head carries at 15 its lower end a ring die punch 23, which is surrounded by a spring held stripper ring 23^a. The said die punch 23 is of a diameter equal to the interior diameter of the ring liner to be cut from a disk blank 14, and the said punch is in vertical alinement with a ring die 24 secured to a hollow vertically reciprocating cross head 24' movably supported beneath the turret or carrier 5, and operated by any suitable means that will cause the upper and lower die members 23 and 24 to approach and recede in relation 20 with each other preferably simultaneously. The said reciprocating members as moved together pass from opposite faces into and partially through one of the positioned openings 15 of the rotatable turret or carrier member 5, the said opening of the carrier member at such time being in vertical alinement with the reciprocating die members 23 and 24, during which movement of the said members the rotatable turret or 25 carrier member 5 is held stationary. At this time or step in the operation of the machine there has been positioned within the said opening 15 of the horizontally rotatable turret or carrier member 5, a disk blank 14, 30 the same being supported therein by the circumferentially disposed shoulder or shelf 16. This disk blank is held to its seat by the face of the reduced section 23^a of the stripper ring 23', which first enters the positioned 35 opening 15 of the rotatable turret or carrier member 5 and bears against the upper surface of the positioned disk blank 14, the die ring 24 at which time reaches the completion of its inward stroke and thus clamps the 40 said disk blank circumferentially between the faces of the stripper ring 23' and the said die ring 24. The die ring punch 23 then continuing its downward stroke for a short distance, due to the yield of the springs 45 23^b of the stripper ring 23^a, cuts from the held disk 14 a central core piece *a* leaving a ring liner *b* of proper size held between the face of the lower reduced end of the stripper ring 23' and the upper face of the ring die 24, the said movement of the die punch 23

carrying the cut core piece *a* into the enlarged portion C of the ring die 24, from which it falls by gravity into the hollow open cross head 24' being deflected therefrom by means of inclined guide rods (not shown) to a suitable place of deposit. On the return or separating stroke of the die punch 23 and the die ring 24, the stripper ring 23' serves to remove or strip the cut ring liner *b* from the punch 23 and leaves the same deposited on the circumferential shoulder or shelf 16 of the opening 15 of the horizontally rotatable turret or carrier member 5. To prevent the cut fibrous central core piece *a* of the disk blank 14 from adhering to the face of the die punch 23, there is provided in said punch one or more air ducts 26' which said ducts are open to the atmosphere and admit air to break or destroy on the return stroke of the said die punch such air suction or vacuum as may have formed and by so doing causing the cut core piece *a* to fall from the punch 23 into the hollow cross head 24'.

On the die punch 23 with its stripper ring 23' and the ring die 24 moving out of the opening 15, a plurality of step movements are or may be imparted to the horizontally rotatable turret or carrier member 5 to place the said opening thereof with the cut ring liner *b* therein in vertical alinement with reciprocating assembling means for placing the cut ring liner *b* onto the flange *d* of a can end or cover plate 13. These step or intermittent rotations of the said turret or carrier member are accomplished by the part rotation imparted to the vertical shaft 4 through the medium of any suitable means such as those shown and described in said patent. The step rotations so imparted to the turret or carrier member 5 are such as to place the opening 15 with the cut ring liner therein in alinement with a vertical opening 27 in the stationary table 2 and in alinement with the vertically reciprocating assembling and marking means for placing the cut ring liner *b* onto the flange *d* of a positioned can end 13 and marking or stamping the same (Fig. 2).

In the present case, the assembling and marking means comprise vertically opposed reciprocating plungers 28 and 28' which plungers are movable into and out of the opening 15 of the horizontally rotatable turret or carrier member 5 containing the ring liners *b* to be applied. The plunger 28 on its downward stroke forces the cut ring liner *b* from its shouldered seat 16 of the opening 15 onto the flange *d* of the positioned can end 13 (Fig. 3), the stem 29 of such plunger working through a guide 29'. The companion plunger 28' lifts the can end 13 from its seat into the opening 15 and holds the same near or against the shelf 16 while the cut ring liner *b* is being forced onto the

flange *d* thereof, the stem 28² of the plunger 28' seating within a socketed connecting member 28³, which works within a vertically disposed guide sleeve (not shown). Within 5 the socketed connecting member 28³ is seated a compression spring 34 for exerting a cushioned action between the stem 28² and the socketed connecting member 28³ and which normally holds the plunger 28' outwardly 10 pressed. The said member 28³ is connected with a stud 34' which projects from the upper end of a lift or actuating rod (not shown), which is vertically reciprocated in unison with the upper plunger 28 in any 15 suitable manner.

In order that the can end 13 may be marked or stamped preferably substantially simultaneously with the application of the ring liner *b* and that the ring liner handling 20 mechanism may be utilized for this purpose, there is provided in the under face of the upper plunger member 28 a preferably circular recess 21 in which is suitably secured a die holder 25 in which in turn is suitably 25 secured a male die member 30. In the upper face of the lower plunger member 28' is a recess 31 in which is secured in proper alinement with the upper male die member a female die member 32.

30 The plunger 28' works through a vertical opening 27 in the fixed table 2 and on its upward movement or stroke lifts the positioned can end 13 into the aligned vertical opening 15 of the horizontal rotatable turret 35 or carrier member 5 until it reaches a position therein immediately beneath the supporting shoulder, shelf or ledge 16 on which rests the positioned cut ring liner *b*. During the upward movement of the plunger 28', 40 the opposing plunger 28 is descending so that by the time the can end 13 has been lifted into proper position within the opening 15 of the carrier member 5, the plunger 28 is acting on the cut ring liner *b* to force 45 the same from its circular seat 16 onto the flange *d* of the can end 13. Substantially at the moment that the ring liner *b* is snapped over the curled portion of the can end flange and is seated within the same 50 50 the upper die member 30 engages the central depressed body portion of the can end and in coöperation with the lower die member 32 embosses or otherwise marks the same.

55 As soon as the can end is marked and applied with a ring liner or other packing medium, the opposed plungers 28 and 28' recede from within the opening 15 in the carrier 5 and the latter is again rotated 60 carrying as it does so the marked and lined can end to a delivery station where the same are discharged through an opening 37 in the table 2 onto an endless conveyer 37' which conveys the same to a suitable place of deposit.

The plunger 28' is or may be provided with an exterior or peripheral ring like part 38 which is yieldingly supported so as to be normally substantially flush with the top surface of the lower die (Figs. 2 and 4) 70 so that the can end, notwithstanding its shoulders and recessed central part, will readily slide onto and off from the plunger. When the plungers 28 and 28' come together to apply the ring liner and emboss the can 75 end the ring liner is first applied and further pressure of the plunger causes the peripheral depending ring of the upper plunger to depress the ring 38, at the same time compressing its yielding supporting 80 springs 39. This depression brings the central part of the can end against the lower die and the two dies then perform the marking or embossing (Fig. 3). When so depressed the ring 38 is received in a per- 85 85 peripheral recess 40 of the lower plunger, it being guided by bolts or screws 41 which pass up through apertures in the lower plunger and are screwed into the under side of the ring 38. As the plungers separate the 90 ring 38 is returned by its springs 39 to its normal flush position, where it is arrested by the heads of the screws 41.

It will be understood that the spring 34 is strong enough to cause the marking de- 95 vices to perform such marking or embossing as is required. Also that the said dies may be reversed in position, with the male die below the can end; also that the die holders and dies are removable and replaceable to vary the mark to be embossed on the can end, as may be desired.

Also, that it is not necessary that the marking be done at the same station where the ring liner is applied, but can be done at 105 a marking station, separate from the lining station; this would still bring about simultaneous lining and marking only that one can end would be lined simultaneously with another being marked, instead of the same 110 can end being lined and marked simultaneously. That is to say, the invention is not confined to applying the ring liner and performing the marking at the same station.

What is claimed is:

1. In a ring liner applying and can end marking machine, the combination of the ring liner applying devices, and can end marking means attached to and operable with the said devices for the simultaneous seating of the ring liners and marking of the can ends, the ring liner applying devices being yieldingly mounted relative to the can end marking means.

2. In a machine for cutting and applying ring liners to shouldered sanitary can ends and for embossing the said can ends, the combination of the ring liner cutting means, the ring liner applying devices movable to apply the ring liners so cut around the 125 130

shoulders of the can ends, mechanism for operating the said cutting means and the applying devices, and embossing dies arranged to operate on the can ends within 5 their shoulders, said dies being situated within the parts of the ring liner applying devices which operate on the ring liners, and being actuated by the said mechanism, the ring liner applying devices being yieldingly mounted relative to the embossing dies.

3. An organized apparatus for the cutting and applying of ring liners to the flange of can ends and marking the can ends, the 15 same comprising a movable carrier member provided with a series of seats, means for supplying liner disk blanks to the said seats, opposing plungers situated within the path of movement of said seats, said plungers 20 adapted to cut a core from said liner disk blank and leave a ring liner on said seat, means for supplying can ends to a point beneath the path of the said seats, and ring liner applying and can end marking means 25 situated in the path of the said seats and cut ring liners, said means comprising upper and lower plunger members, and a marking member secured to the face of one of said plungers, said plungers being adapted 30 to substantially simultaneously remove said ring liner from its said seat to the can end flange and operate said marking member to mark the can end, the ring liner applying means being yieldingly mounted relative to 35 the can end marking means.

4. The combination with a member having a perforation and a shoulder within the same, of a bottom plunger for lifting a can end to said shoulder, a top plunger having 40 a flange for pressing a ring liner down past said shoulder and into the can end, and marking means on said plungers operating through the said aperture and through the central aperture of the ring liner and 45 by the ring liner-inserting movement of the plungers, the marking means of the can end supporting plunger being movable relative to the can end supporting part of said plunger.

50 5. The combination of a laterally movable member having a perforation and a shoulder therein, a fixed part below said member having an aperture, means for sliding a shouldered can end, with its concave side downward, along the surface of said fixed part and in line with said perforation and shoulder, a plunger operating through the aperture in said fixed part, marking means carried by said plunger and retract-

able to the plane of said surface, and an opposing plunger operating on the convex side of the can end.

6. The combination of a plunger for engaging a can end on its dished side and formed with separately movable and operable outer and inner parts, the outer part 65 adapted to operate for the seating of a ring liner and the inner part having a marking die; and opposing pressure means having an annular flange adapted to seat a ring liner on the flange of the can end and having a die adapted to coöperate with the first mentioned die.

7. The combination of a plunger for engaging a can end on its dished side and 75 formed with separately movable and operable outer and inner parts, the outer part adapted to operate for the seating of a ring liner and the inner part having a marking die; and an opposing pressure plunger having 80 an annular flange adapted to seat a ring liner on the flange of the can end and having a die adapted to coöperate with the first mentioned die.

8. The combination of a plunger for engaging a can end on its dished side and formed with separately movable and operable outer and inner parts, the outer part 85 adapted to operate for the seating of a ring liner and the inner part having a marking die, springs interposed between said parts; and opposing pressure means having an annular flange adapted to seat a ring liner on the flange of the can end and having a die 90 adapted to coöperate with the first mentioned die.

9. The combination of a plunger for engaging a can end on its dished side and formed with separately movable and operable outer and inner parts, the outer part 100 adapted to operate at the first part of the movement of the plunger for the seating of a ring liner and the inner part having a marking die and operating at another part of the movement of the plunger; and opposing pressure means having an annular flange adapted to seat a ring liner on the flange of the can end and having a die 105 adapted to coöperate with the first mentioned die.

In testimony whereof we affix our signatures hereto.
